FOUNTAIN BRUSH

John M. Ross, 3660 Monroe,
Dearborn, Mich. 48124

Filed Mar. 5, 1973, Ser. No. 338,378

Term of patent 14 years

Int. Cl. D4—01

U.S. Cl. D4—7

FIG. 1 is a front elevational view of a fountain brush, embodying my new design.

FIG. 2 is a top plan view thereof.

FIG. 3 is a side elevational view thereof.

I claim:

The ornamental design for a fountain brush, as shown.
